UNITED STATES PATENT OFFICE

JOHANNES MENSCHNER, OF ROSSWEIN, GERMANY, ASSIGNOR TO KOCH & TE KOCH,
A FIRM, OF OELSNITZ, GERMANY

CARD SAVING MOTION FOR JACQUARDS

Application filed February 4, 1930, Serial No. 425,762, and in Germany February 8, 1929.

This invention relates to a card saving motion for jacquard operating mechanisms, the object of the present invention being to provide a card saving motion or multiplier 5 of greater utility than existing motions of this kind.

For this purpose the invention consists in the provision of a timing disc for each of certain of the griff hooks, each of said timing discs being adapted to release the further feed of the jacquard card after a variable predetermined number of picks. The griff mechanism is kept stationary for the same predetermined number of picks.

Such a card saving motion, within the maximum number of repetitions permitted by its timing discs, enables any desired work to be so controlled that the jacquard cards remain at rest during every period of repetition which occurs. It is only necessary to have the proper markings on the cards whether it be the main card or a special saving card and from such markings the operation of the mechanism may manually be 25 placed in operation.

According to the invention the card saving motion mechanism is more particularly actuated directly by the griff hooks by the provision of transmission rods whereby each 30 griff hook directly drives its own timing disc which provides for the desired number of repetitions.

The accompanying drawings illustrate one constructional example of card saving mechanism according to the present invention. Fig. 1 is a diagrammatic side view partly in section and Fig. 2 is a view at right angles to Fig. 1.

The card cylinder shown by dotted lines is 40 designated by the reference numeral 1 and the arrow 2a indicates the direction of the pull effected by any selected griff hook 2. Movement of a griff hook is transmitted by a bell crank lever 3 and rod 4 to the card mechanism, whilst a spring 5 acting in the 45 direction of the arrow 5a against a stop 6 on the rod 4 returns the griff hook to its original position after every actuation. The rod 4 transmits its movement by a lever 7 50 to a shaft 8 and through the shaft to a lever

9. Arms 12 mounted in bearings 11 at both sides of the frame or mechanism support a shaft 15 carried by the arms 12 on which are freely rotatable side by side a plurality of feeler members 16, for example, ten of them. Cams 13 on a driving shaft 14 cooperate with rolls 46 on the shaft 15 and impart thereto an up and down motion together with its arms 12 and the several feeler members 16. Although not shown on the drawings it is to be understood that there will be an equal number of levers 9 and 7, rods 6 and griff hooks 2. The upper end 18 of each feeler member 16 is constructed in the form of a pawl which is 65 pressed by a spring 17 towards a timing disc 19, one of which is provided for each feeler member, the timing discs being loosely mounted side by side on a shaft 20. The pawls 18 can only follow the pull of the 70 spring 17 when the corresponding lever 9 is pulled by the griff hook appertaining thereto and when it has assumed the position shown in Fig. 1. The discs 19 have ratchet teeth spaced and of such a pitch 75 that at every upward motion during the operation of the machine a feeler member 16 released by the pull of its griff hook, feeds its timing disc forward a distance of one tooth. Thus, all feeler members 16 are 80 swinging up and down in such fashion that they do not engage their appertaining counting discs. Only that feeler which is released by the pull of its griff hook moves into engagement with its counting disc. It 85 slides (during its downward movement) simply over the back of a tooth and drops into the recess of the next tooth. During its upward movement, it is again fed forward for one tooth and this is repeated until 90 it drops into the deep groove which leads to the forward feeding of the cylinder shaft. Then the griff hook pull of this feeler member stops and a spring 5 begins to act, whereupon the feeler member is 95 pulled out of said deep groove by means of lever 9 and the said spring 5. On each of these discs at a distance apart equal to a certain number of ratchet teeth which varies on each disc, there is a deep notch 10 into 100

which the feeler member engages when released by its griff hook to carry with it a rod 21 which is connected and carried by an arm 22 on the shaft 15 and thus also takes with it an arm 23 on the same shaft. The arm 23 has a projecting member 24 which acts as a pawl and which thus engages the ratchet wheel 25 for feeding the jacquard cylinder and feeds the same forward a distance of one tooth. When the pull of the griff hook relaxes, the feeler member 16 is swung back about its pivotal shaft 15 by means of the lever 9 acted on by the spring 5 and the arm 23 also leaves its effective position under the action of a spring 26 and an eccentric 27, on a shaft which is driven by a gear on shaft 42, so that it only effects a single forward feed until it is again brought into its effective position by another feeler member after the lapse of a further number of picks.

The timing discs must be so arranged that on each disc the number of notches 10 will divide one or more times into the number 25 of ratchet teeth. Therefore they will not all be of the same diameter and the pitch of the ratchet teeth will vary to some extent with the length of the downward stroke of the feeler members.

30 In case the use of the card saving motion should appear to be temporarily or for a time wholly of no advantage, perhaps because cards of identical punching are only to repeat two or three times, the following 35 mechanism is provided. A spring 28 by means of a rod 29 pulls double lever 30 downwards, the double lever being loosely mounted on the shaft 15 so that its free arm 31 brings the arm 23 with its pawl 24 40 constantly into cooperation with the ratchet wheel 25, when a feeler member 16 is not actuated by the griff hooks. If on the contrary, as previously described, a griff hook is actuated and thus one of the levers 45 9 is moved into the position shown in Fig. 1, it carries with it a rod 32 which extends across the several levers 9. The rod 32 is carried by arms 33 which swing about the shaft 8 and one of the arms 33 moves a lever 50 34 which moves the rod 29, together with the double lever 30, 31, into its inoperative position as shown in Fig. 1 against the action of the spring 28.

55 By exerting a pull on any one of the levers 9, the double lever 30, 31 will therefore be brought every time into its inoperative position by the aid of the rod 32. By means in themselves known for instance as set forth on patent to C. Novet No. 785,679, 60 dated March 21, 1905, the griffe block 35 is prevented from carrying out its stroke until the ratchet wheel 25 is fed forward.

65 For this purpose, for example, a swinging lever 37 is provided on the frame in such manner that it is drawn by a spring

38 into a position against a stop 37' in which position it is beneath an extension 39 of an arm 40 which moves the griff block up and down and thus prevents its movement. If the saving motion is out of operation, the 70 card shaft 41 is fed forward through one tooth of the ratchet wheel 25 while the shaft 42 continues to rotate. Together with the card shaft rotates a lantern wheel 43 which successively moves the nose of a lever 44 75 sideways. The lever 44 is articulated to the swinging lever 37. It thus moves the swinging lever at every forward feed into a position in which it no longer prevents the downward movement of the arm 40 and it is then lifted up by a non-circular disc 45 80 on the shaft 42, so that it is free from the lantern wheel 43 with which it was in engagement and is returned with the swinging lever by the spring 38. The swinging lever 85 then moves again under the arms 40 which in the interval have completed the griff block movement and have reached their upper position. If now the saving motion becomes operative, the feeding of the card shaft ceases and the lever 44 is not drawn sideways but is only raised and lowered without effect by the non-circular disc 45 at each rotation of the shaft 42. Consequently the swinging lever 37 also remains 90 in the position illustrated arresting the movement of the arms 40.

95 As an example of the manner in which the mechanism operates, it may be assumed that it is to be used in conjunction with a loom for chenille cloth and is to control the change of the weft. The jacquard card must have a hole for each of the different coloured threads to be picked and for each of the 100 timing discs 1-10.

105 The card holes are engaged by the needles which operate the relative hooks. When the griff block 35 descends, the hooks engage the griff knives and are raised with the griff when the latter rises. At the same time, for example, by means of the saving hook 2, the bell crank lever 3 and the pull rod 4 pull the levers 7 and 9 and release one of the feeler members 16 which by means of the spring 17 is pressed against the timing disc 19 having ten ratchet teeth. Nine of the ratchet teeth of this disc have only shallow notches whilst the tenth is a deep notch. The feeler member 16 now feeds 110 at the same rate as the picking operation first the nine teeth with the shallow notches and then finally the tooth with the deep notch. Thereupon the feeler member 16 presses against the rod 21 and the lever 23 connected therewith, together with its arm 24 115 against the feed wheel 25, which is thus fed forward one tooth by the lifting of the arm 23, thus the card cylinder 1 and the card is again fed forward one step and at the same time the swinging lever 37 which prevents 120

movement of the extension 39 of the arm 40 is withdrawn by one of the pins of the lantern wheel 43 and the lever 44. In this manner the lever 40 and the griff block 35 are caused to descend and on rising can lift with them the griff hooks in the meantime set by the jacquard machine for the new colour and saving motion. The non-circular disc 45 on the shaft 42 presses the lever 44 out of the reach of the lantern wheel 43 and the spring 38 pulls the swinging lever 37 under the extension 39 of the lever 40 which in the interval has again been raised, and the whole operation repeats with another feeler member which now enters into operation.

I claim:

1. A jacquard card saving motion comprising a set of griff hooks or saving hooks, a timing device associated with each of said hooks, and mechanism whereby the feed of the card cylinder is interrupted until said timing device permits the further feed of the card cylinder after a definite number of picks determined by said timing device.
2. A jacquard card saving motion provided with a series of pawls actuated in synchronization with the machine picks, a series of timing discs having ratchet teeth for cooperating with said pawls, each of said discs having one or more deep notches, a card feeding ratchet wheel, a driving member cooperating with said ratchet wheel, a series of griff hooks, and mechanism interconnecting said griff hooks and pawls whereby the lifting of a griff hook causes its associated pawl to rotate its timing disc step by step until the notch in said disc is brought into operative position, whereupon the feed wheel is fed forward one step by the driving member.
3. In a jacquard motion including a series of pawls and a series of griff hooks, the combination of a movable rod extending across the several pawls, means for moving said rod so as to normally hold said pawls in their inoperative positions, said rod being moved by the lifting of one of the griff hooks to allow the pawl associated with said griff hook to assume its operative position, and mechanism for normally holding a driving member in engagement with the feed wheel and for withdrawing said driving member when one of the griff hooks is lifted.
4. A jacquard card saving motion comprising a series of griff hooks, a corresponding series of pawls, a series of spring-controlled connections between the griff hooks and their associated pawls, mechanism for constantly reciprocating said pawls, a series of ratchet timing discs one for each pawl, each of said discs having a deep notch therein, means for normally holding said pawls out of operation with their ratchet discs, means for causing each of said pawls to engage its

discs when its associated griff hook is pulled, a card feed wheel, a feed member reciprocated with said pawls and normally held in engagement with said feed wheel, mechanism for moving said feed member out of engagement with the feed wheel when a griff hook is operated, said feed member being returned into engagement when one of said pawls drops into the notch in its associated feed wheel.

Signed at Dresden, Germany, this 14th day of January, A. D. 1930.
